(57) **CLAIM**

I claim the ornamental design for eyewear, as shown and described herein.

DESCRIPTION

FIG. 1 is a perspective view of my eyewear with the frontal portion shown in the open position;

FIG. 2 is a view similar to FIG. 1 showing the frontal portion in the closed position;

FIG. 3 is a front view of my eyewear;

FIG. 4 is a rear view thereof;

FIG. 5 is a top view thereof;

FIG. 6 is a bottom view thereof; and,

FIG. 7 is a right side elevational view with the left side elevational view being a mirror image thereof.

The broken lines shown are for illustrative purposes only and to which no claim is made.
